(57) **CLAIM**

The ornamental design for the display screen or portion thereof with animated graphical user interface, as shown and described.

DESCRIPTION

FIG. 1 is a front view of first image in the sequence of a display screen or portion thereof with animated graphical user interface showing my new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof; and,

FIG. 9 is a front view of a ninth image thereof.

The broken lines showing a display screen or portion thereof and elements of the graphical user interface illustrate portions of the article, and form no part of the claimed design. The graphical user interface transitions sequentially between the images shown in FIGS. 1-9. The process or period in which one image transitions to another forms no part of the claimed design.
